UNITED STATES PATENT OFFICE

DAVID B. COOK, OF FRANKFORT, NEW YORK, ASSIGNOR TO ACME ROAD MACHINERY COMPANY, OF FRANKFORT, NEW YORK, A CORPORATION OF NEW YORK

ROAD MACHINERY

Application filed January 28, 1926. Serial No. 84,299.

My invention relates to road machinery, and has special reference to road rollers, tractors and graders.

An object of the invention is to generally improve this class of road machinery as will hereinafter appear.

Another object of the invention is to provide a road grader in which the grading device is mounted in a novel and improved manner.

Another object of the invention is to provide a road grader having actuating mechanism for the grading device which is simple in construction, efficient in operation, and easily controlled by the operator.

Another object of the invention is to provide a road vehicle which may be easily converted into a three-wheel road roller or four-wheel tractor.

With these and other objects in view, the features of the invention consist in certain constructions, arrangements and combinations of parts hereinafter described and claimed, the advantages of which will be obvious to those skilled in the art.

The several features of the invention will be clearly understood from the following description and accompanying drawings, in which:

Figure 1 is a plan view, partly in section, of a three-wheel road roller embodying features of the invention in their preferred form;

Fig. 2 is a side elevation, on an enlarged scale, of a portion of the same;

Fig. 3 is a sectional plan view taken on the line 3—3 of Fig. 2;

Fig. 4 is a detail sectional view taken on the line 4—4 of Fig. 3;

Fig. 5 is a detail plan view, on an enlarged scale, corresponding to a portion of Fig. 1 but showing certain parts in section, illustrating especially the operating mechanism for the grading device;

Fig. 6 is a sectional elevation of the forward portion of the vehicle when converted into a four-wheel tractor, taken substantially on the line 6—6 of Fig. 7; and

Fig. 7 is a sectional plan view taken substantially on the line 7—7 of Fig. 6.

The three-wheel road roller illustrated in the drawings is provided with a chassis or frame 2, a pair of rear rollers 4, a front roller 6, and an internal combustion engine 8. The chassis 2 comprises longitudinally extending angle irons or beams 10 that are connected at their rear ends by a transverse bar 12 and are further connected by suitable struts or braces (not shown). The rear rollers are mounted on an axle 14 which extends through suitable bearings in the side beams 10. The front roller 6 is mounted in the usual yoke 16 which is provided with an upright bull pin 18 that extends through and is journaled in a bearing in the forward end of a saddle 20 having rearwardly projecting supporting arms 22 which are secured by bolts 24 to the outside of the forward ends of the side beams 10. The front roller is adapted to be turned to steer the roller by means of the usual segmental gear 26 secured to the bull pin 18 and engaged by a worm 28 which is operable by means of the usual steering post 30, the steering wheel 32 of which is in a convenient position to be grasped by the driver from a seat 33.

The internal combustion engine 8 is suitably mounted upon the chassis between the side beams 10. This engine is provided with the usual radiator 34 on its forward end, and housing 36 on its rear end that is secured to the engine casing and encloses the differential and differentially driven shaft 38. The engine is of a common type used on tractors, the differentially driven shaft 38 being the driving axle when thus used. In the illustrated construction pinions 40 are secured on the ends of the shaft 38 and engage internal gears 42 on the rear rollers 4, thus providing a differential drive for the rear rollers.

Upright angle irons 44 are secured by bolts 46 to the outer sides of the supporting arms 22 of the front roller saddle 20 adjacent the extreme forward ends of the angle irons or beams 10. Similar uprights 48 are secured to the longitudinally extending beams 10 adjacent the rear end of the engine casing. The upper ends of each pair of angle irons 44 and 48 are connected by a transverse angle iron 50.

which extends over the engine casing, and the upper ends of the angle irons 44 and 48 at each side of the engine are connected by a longitudinally extending angle iron 52. 5 Spaced angle irons 54 have their ends secured upon the longitudinally extending angle irons 52.

The road roller illustrated in the drawings is further provided with a road grading device which is mounted in a novel and improved manner. As shown, this road grading device comprises the usual grading blade 56 that extends transversely beneath the frame of the roller. It may here be noted that the 10 construction of the roller is such as above described, that the frame is spaced a considerable distance from the ground, and thus ample space is provided for the operation of the grading device. The blade 56 is mounted 15 upon the forward end of a supporting structure 58 which comprises two angle irons 60 having their rear ends separated and pivotally mounted on a rod or pin 62 that extends through apertures in the lower ends of 20 hangers 64 secured to the undersides of the beams 10, the rear ends of the angle irons 60 being arranged adjacent the inner side of the hangers. The forward ends of the angle irons 60 are brought together and secured to 25 a block 66 which has forwardly extending ears 68 which receives a tongue 70 between them, the tongue being pivotally mounted on a vertical pin 72 extending through the ears. The forward end of the tongue 70 is pivotally 30 mounted on a horizontal pin 74 which extends through rearwardly projecting ears on a bracket member 76 secured at the center of the lower portion of the grading blade 56. The pivot pin 62 for the supporting structure 35 58 is located at a point arranged substantially one-half the distance between the under side of the frame beams 10 and the ground and is spaced a slight distance in front of the vertical plane extending through the axis of 40 the rear rollers.

An adjusting segment 78 for the grading blade is connected with the blade by means of forwardly and downwardly extending brackets 80 secured on the ends of the blade and 45 having their forward ends pivotally connected with brackets 82 secured to the rear side of the grading blade near the ends thereof. The segment 78 is provided with notches 84 that are adapted to receive the end of the 50 usual locking pawl or spring-pressed plunger 86 which is adapted to be retracted from the segment by means of the usual rod 88 having a handle on its upper end which is in position to be grasped by the driver. The rim 55 of the segment 78 works through forwardly projecting flanges 90 formed on a block 92 in which the locking pawl or plunger 86 is mounted, the flanges being spaced a distance above and below the rim of the segment. The 60 grading blade is adapted to be tipped trans-

versely upon the pivotal connection between the blade and the brackets 80, and the pivotal connection between the blade and the tongue 70, and is adapted to be held in the position thus adjusted by means of links 93 having 70 their forward ends pivotally connected with the blade and having their rear portions extending between ears 94 secured to a bar 96 having its ends secured to the segment 78. Each link 93 is provided with a series of 75 spaced apertures 98 so as to permit a locking pin 100 to be passed through apertures in the ears 94 associated therewith and through any one of the apertures.

With this construction it will be apparent 80 the grading device may be raised and lowered together with its supporting structure 58 about the pivot pin 62, that it may be turned about its pivotal connection with the supporting structure 58 and held in adjusted position by the engagement of the locking pawl or plunger 86 in a notch in the segment 78, and that it may be tilted transversely and 85 held in adjusted position by the links 93 and locking pins 100. Also there is sufficient 90 looseness of parts in the pivotal connection between the grading blade and the supporting structure 58 to permit the blade to be tipped to raise or lower either end thereof, the clearance between the rim of the segment 78 and the flanges 90 being sufficient to allow for 95 such tipping of the blade and the segment with relation to the supporting structure 58.

In the illustrated construction power operated means, which may be conveniently controlled by the operator from the driver's seat, is provided for tipping the grading blade to raise and lower either of its ends, and for bodily raising the blade and its supporting structure. To provide for this, upright lead 100 screws 102 are rotatably mounted at opposite sides of the frame of the roller. Each screw 102 has its lower end journaled in a suitable bearing in a bracket 104 secured to one of the angle irons or frame beams 10, and has 105 its upper end extended through and journaled in a suitable bearing 106 in the corresponding longitudinally extending angle iron 52 that is arranged above the engine. A block 108 is screw-threaded on each lead 110 screw 102, and has laterally extending sheet metal arms 110 secured on the sides thereof and connected with the corresponding end portion of the grading blade by means of a rod or link 112 having its upper end pivotally 115 mounted on a pin 114 extending through apertures in the outer ends of the arms 110, and having its lower end pivotally connected with an eye lug 116 secured on the bracket 80 connected with the blade. With this construction, upon turning either lead screw 102, the block 108 associated therewith may be 120 raised and lowered and through the link 112 the corresponding end of the grading blade 125 may be raised and lowered as desired, and 130

when the two screws are operated simultaneously in the same direction, the grading device and its supporting structure 58 may be raised and lowered about the axis of the pivot pin 62 that supports the structure. A bevel gear 118 is secured on the upper end of each lead screw 102, and is engaged by a pinion 120 secured on the outer end of a transverse shaft 122, the two shafts 122 being arranged end to end and having their inner ends journaled in a bearing block 124 supported by a bar 126 extending between the transverse angle irons 54, and having their outer ends extending through and journaled in bearings 128 on casings 130 that enclose the bevel gears 118. Each of the transverse shafts 122 carries a spur gear 132 which engages a gear 134 loosely mounted on a shaft 136, which has its ends journaled in bearings 138 formed on the rear side of the gear casings 130. Each of the shafts 122 also carries a sprocket wheel 140 which is connected by a chain 142 with a sprocket wheel 144 loosely mounted on the shaft 136. The spur gear 134 and sprocket wheel 144 for driving each shaft 122 carry opposed conical friction clutch members 146. Each pair of clutch members 146 is adapted to cooperate with male friction clutch surfaces formed on a clutch sleeve 148 which is keyed to and mounted to slide longitudinally on the shaft 136. Upon shifting each clutch collar 148 in one direction to the spur gear 134 associated therewith may be clutched to the shaft 136 so as to drive the associated transverse shaft 122 in one direction. Upon shifting each clutch sleeve 148 in the opposite direction the spur gear 134 may be disconnected from the shaft 136 and the sprocket wheel 144 connected with the shaft to drive the associated transverse shaft 122 in the opposite direction. Thus it will be apparent that by properly shifting the clutch sleeves 148, either one or both of the upright screws 102 may be rotated in either direction either simultaneously or independently of each other, and thus the grading blade may be tipped to raise or lower either one of the ends of the grading blade 56, or the blade and its supporting structure may be raised or lowered.

The clutch sleeves 148 are adapted to be conveniently shifted by the operator by means of levers 150 pivotally mounted on the rear transverse angle iron 54. Each lever 150 has its forward end in the form of a yoke which engages the usual annular groove 152 in the associated clutch sleeve, and has its rear end provided with a handle that is in convenient position to be grasped by the operator from the driver's seat. The shaft 136 is adapted to be continuously driven from the usual power take-off shaft 154 of the engine, through a sprocket chain 156 which passes over a sprocket wheel 158 secured on the shaft 136 and a sprocket wheel 160 secured on the end of the power take-off.

It will be apparent that the arrangement of the supporting structure 58 of the road grading device, and the location of the pivotal connection of its rear end with the frame of the roller at a point in proximity to a vertical plane passing through the axis of the rear rollers and substantially midway between the underside of the frame of the roller and the ground, permits effective operation of the device without any material interference with the steering of the roller, as is the case where the supporting structure is mounted on the forward part of the frame of the roller or tractor as heretofore. The power operated means for raising and lowering the device is of simple construction, takes up but little room, is conveniently controlled by the operator, and may be operated without the necessity of stopping the roller or interfering with the operation thereof.

The illustrated construction is adapted to be easily converted from a three-wheel road roller into a four-wheel tractor. To provide for this the rearwardly projecting arms 22 of the saddle for the forward roller 6 are detachably secured to the outside of the forward end portions of the side beams 10 of the frame of the roller, the bolts 24 and 46 being removable. When the front roller saddle is thus removed, a front two-wheel truck of novel and improved construction may be applied. This truck, which is illustrated in Figs. 6 and 7 of the drawings, is provided with the usual tractor wheels 162 that are mounted through the usual knuckle joints 164 on the ends of an axle 166 which is secured between depending plates 168 by a bolt 170 extending through apertures in the plates. These plates are secured to the sides of a channel iron 172. A wish bone or radius rod 174 is secured to the rear sides of the axle and has its rear end secured by a bolt 176 to a depending plate 178 which is secured to an angle iron 180. The channel iron 172 and the angle iron 180 are secured to the under sides of the front and rear ends of longitudinally extending angle irons 182 which are secured to the inner sides of angle irons 183. These angle irons 183 are secured to the under side of a plate 184 which is secured to the under sides of longitudinally extending angle irons 186 having their forward ends secured together by an angle iron 188. The angle irons 186 are spaced the proper distance apart to permit their rear ends to be applied to the outer sides of the forward end portions of the angle irons or frame beams 10. The rear end portions of these angle irons 186 have bolt holes which register with the bolt holes in the forward end portions of the frame beams 10, and when applied are adapted to be secured to the beams 10 by means of the bolts 24. The angle irons 186 are also provided with bolt holes for receiving the bolts 46 which

secure the lower ends of the standards 44. The front truck is provided with the usual steering mechanism, comprising the arms 190 projecting from the knuckles 164 and connected by a rod or link 192, and operable through an arm 194 projecting from one of the arms 190, and a rod 196 which may connect the outer end of the arm 194 with the steering post 30 in a well known manner.

As will be evident to those skilled in the art, my invention permits various modifications without departing from the spirit thereof or the scope of the appended claims.

What I claim is:

1. A road vehicle having, in combination, a frame, a road grading device mounted beneath and extending transversely of the frame, blocks mounted for up and down movement adjacent the sides of the frame, a shaft, means for driving the shaft, and connections between said blocks and shaft for raising and lowering the blocks independently of each other at the will of the operator, and connections between said blocks and the ends of said device for raising and lowering said ends.

2. A road vehicle having, in combination, a frame, a motor mounted on the frame for propelling the vehicle, a portion of said frame extending over the motor, a road grading device arranged beneath and extending transversely of the frame, rotatable upright screws arranged at the sides of the frames, blocks mounted on said screws adapted to be raised and lowered upon rotation of said screws, connections between said blocks and the ends of said grading device for raising and lowering said ends with said blocks, respectively, a shaft mounted on the frame above said motor and extending transversely thereof, connections between said shaft and motor for driving the shaft, and connections between said shaft and screws for rotating the screws independently of each other at the will of the operator.

In testimony whereof, I have signed my name to this specification this 20th day of Oct., 1925.

DAVID B. COOK.
